UNITED STATES PATENT OFFICE

JOSEPH WOLFINGER, OF DUNDAS, WISCONSIN

CAN WASHING DEVICE

Application filed October 7, 1929. Serial No. 397,933.

This invention relates to improvements in can washing devices.

One of the objects of my invention is the provision of a can washing device which is particularly adapted for use in cleansing metal cans which are used in the process of canning fruits, vegetables, and the like so as to thoroughly cleanse these cans before the material is placed therein to be sealed.

10 Another object of the present invention is the provision of a can washing device wherein the cans are fed through the machine in an inverted position with fluid injected into the interior of the cans as they pass through the machine so as to thoroughly cleanse the cans while being passed through the machine.

A further object of the invention is the provision of a can washing machine wherein the cans are passed into the machine in a substantially horizontal position, are then moved to an inverted position with jets of cleansing fluid directed into the interior of the inverted cans to thoroughly cleanse them and then have the cans returned to a horizontal position upon leaving the machine, together with means whereby the machine is thoroughly drained of any accumulation of water so as to maintain the same in a sanitary condition.

20 A still further object of the invention is the provision of a can washing device wherein the cans are slowly moved through the machine and the movement of the cans is controlled by a manipulated operated device which also controls the flow of cleansing fluid into the machine whereby when the cans are moving through the machine, the cleansing fluid is turned on and when the movement of the cans through the machine is stopped, the supply of cleansing fluid will be simultaneously cut off.

With the above and other objects in view, the invention consists in the novel features of construction, the combination and arrangement of parts hereinafter more fully set forth, pointed out in the claims and shown in the accompanying drawings wherein:

Figure 1 is a side elevation of a can washing device constructed in accordance with my invention and illustrating the same supported in operative position;

Figure 2 is a plan view on a somewhat larger scale than the showing in Figure 1;

Figure 3 is a detail vertical section taken on the line 3—3 of Figure 2;

Figure 4 is a transverse section on the line 4—4 of Figure 3; and

Figure 5 is a detail section on the line 5—5 of Figure 2.

Referring more particularly to the drawings, it will be noted that I provide an elongated housing 1 having a comparatively large opening 2 in the top thereof which is normally closed by means of a cover 3. One end of the top portion is provided with a receiving opening through which the cans are passed, suitable guide means 4 being provided on the top of the housing for receiving the cans in a horizontal position whereby the cans are fed downwardly through the opening 5 on the top onto the interior guide 6. This interior guide is so arranged that while the cans are fed into the housing 1 in a substantially horizontal position, the inner end of the guide is spiral for turning the cans to an inverted position whereby they travel through a substantially rectangular guide part 7, the lower portion of which is open to receive therethrough the fluid jets 8 issuing from the nozzles 9 which are located directly beneath the substantially rectangular guide part 7.

The cans are fed through the guide part 7 directly above the fluid jets 8 so that the fluid will pass upwardly into the interior of the cans and thoroughly wash the same, this operation being fully illustrated in Figure 4. After the cans have passed the nozzles 9 and pass the exit end of the guide 7, they are directed into a second spiral guide 10 which returns the cans to a horizontal position and directs them onto a guideway 11 where they are conveyed off for use.

The nozzles 9 are supported by and have communication with a substantially horizontal pipe 12, one end of which is connected to the feed pipe 13 in which is arranged a control valve 14, the other end of the pipe leading out of the housing in any suitable manner.

In order that the cans will be continuously

5 moved through the guides and be disposed in an inverted position above the nozzles 9, I provide a rotatable member 14' having radially projecting arms 15, the outer ends of which are formed with rounded sleeves 16 to engage the cans, as shown in Figure 3. This rotatable member 14' is mounted upon the inner end of a horizontally disposed shaft 17 and keyed for sliding movement upon the shaft is a grooved pulley 18 engaged by a yoke 19 on a pivoted lever 20.

10 The outer end of the shaft 17 is preferably threaded and is supported in a suitable bearing 21 exteriorly of the housing and mounted upon the shaft and engaging the inner face of the bearing is a nut 22, while a washer nut 23 is loosely mounted upon the other end of the threaded portion. Arranged upon the shaft 17 for rotative movement relative to the shaft is a pulley 24 which comprises a 15 main disc 25, a friction disc 26 and a clamping drum 27. The main disc 25 is freely rotatable upon the shaft 17 and has a key operating in an annular groove 28 in the shaft 20 whereby to maintain this disc against sliding movement on the shaft. The clamping drum 27 is provided with a sleeve 29, one end of which is engaged by the nut 23, while the friction disc 26 is arranged between the drum 25 and the disc 20.

25 It will be apparent from the foregoing that friction between the drum 27 and disc 25 can be adjusted by the coil spring 30 mounted on the threaded end of the shaft 30 between the nut 22 and washer nut 23 and will maintain the drum 27 in an adjusted position.

35 As the pulley 24 is freely rotatable upon the shaft 17, movement can be conveyed to a finger 31 which projects laterally from the pulley 24, engaging a finger 32 which extends radially from the pulley 18. These two fingers are brought into engagement through the sliding movement of the pulley 18 on the shaft 17.

40 The lever 20 is pivotally mounted upon a suitable bracket 33 carried by the housing 1 by means of the pivot bolt 34. The outer free end of the lever is movable in a guide 35 and has a handle portion 36 whereby the lever may be manipulated and as the lever is connected to the control valve 14, it will be noted that when the pulley 18 is adjusted on shaft 17 for imparting a rotative movement to 45 shaft 17, the valve 14 will be opened, providing a supply of fluid to the nozzles 9. When the shaft 17 is rotated, the arms 15 engage the cans in the guide 6 and move the cans forwardly through the guides 6 and 7 50 where, while the cans are passing through the guide 7, fluid jets 8 will be directed upwardly into the interior of the cans for thorough cleansing them.

55 It will be noted from the above construction that when the clutch mechanism between

50 pulley 24 and shaft 17 is disengaged, the valve 14 is likewise closed simultaneously so that when there is no movement of the cans through the guideways, there will be no supply of cleansing fluid.

55 In order to take care of the waste water during the washing of the cans as they pass through the housing, a drain pipe 37 is arranged for communication with the bottom of the housing so that the water, after being directed into the cans and thence onto the bottom of the housing, can be carried off through the drain pipe 37.

60 In controlling the washing device for use, it is preferred to have the housing 1 supported in a slightly inclined position so that the waste water will always flow toward the waste pipe 37 and as illustrated in Figure 1, the housing is supported upon suitable cross pieces 38, the ends of which project beyond the sides of the housing and have passed therethrough the supporting rods 39, the upper ends of which are connected to the ceiling of the building in which the device is installed, while the nuts 40 are threaded on the lower ends of the rods for supporting the cross pieces 38. Attention is also directed to the fact that the standard 21 for the outer end of shaft 17 is also carried by one of the cross pieces.

65 In order to provide power for the device, a belt 41 is passed around pulley 24 and may be connected to any suitable source of power.

70 From the above description taken in connection with the accompanying drawings, it will be apparent that I have provided a very simple and inexpensive washing device whereby the cans may be readily passed into the device and then passed through the same by means of suitable guides which move the machine to an inverted position and then return them to a horizontal position, the cans being moved forwardly in consecutive order so that one follows directly behind the other and in intimate contact. By feeding the cans in this manner, the cans will be consecutively passed over the nozzles 9 so that they will all receive the jets of cleansing fluid from the nozzles whereby, after the cans have passed the nozzles 9 they will be assured of a thorough cleansing before being returned to their horizontal position.

75 It will also be noted that the housing will be thoroughly drained as the waste outlet 37 is located adjacent the lowermost end of the housing so that all of the waste cleansing fluid will be directed toward this end of the housing and pass out through the waste pipe.

80 Another feature which I wish to call attention to is the fact that the major portion of the top wall of the housing is open and is normally closed by means of the cover 3 whereby this cover may be removed in case the cans get stuck in the guides or if anything gets

out of place with the nozzles or fluid feeding apparatus.

It will also be noted that when the clutch mechanism is operated to create the movement of the cans, the cleansing fluid is turned on so as to assure a continuous supply of cleansing fluid as the cans are passed through the device.

While I have shown and described the preferred embodiment of my invention, it will be apparent that slight changes may be made in the construction when putting the invention into practice without departing from the spirit of the same or the scope of the appended claims.

I claim:

1. In a can washing device, an elongated housing, a guide extending into the housing at one end for receiving the cans in a horizontal position, a central rectangular guide with a spiral guide connecting the first guide and the central guide whereby to move the cans from a horizontal to an upended position, means for injecting fluid into the upended cans as they pass through the central guide, a feeding device including a rotor having radially disposed arms movable in the path of the cans in the first guide for engaging said cans and forcing them through the spiral guide and into the central guide, and means for simultaneously imparting movement to the rotor for moving the cans through the guides and turning on the fluid supply for cleansing the cans as they pass through the central guide.

2. In a can washing machine, an elongated housing, a guide for receiving the cans into the housing in a horizontal position, a central rectangular guideway in the housing, means for moving the cans from a horizontal to an upended position while being passed to the central guide, a plurality of nozzles arranged beneath the central guide for injecting a cleansing fluid into the cans as they pass therethrough, a valve for controlling the flow of cleansing fluid to the nozzles, a shaft extending horizontally through the housing, a rotor on the shaft, radially disposed arms carried by the rotor and movable in the path of the cans in the first guide, whereby to engage the cans and force them through the housing, a grooved pulley keyed to the shaft, a drive pulley loosely mounted thereon, engaging fingers carried by the two pulleys adapted to cooperate for rotating said shaft and a pivoted lever having one end engaging the grooved pulley and the other end connected with the fluid control valve whereby to simultaneously impart movement to the rotor for moving the cans through the guides and actuate the valve for supplying fluid to the nozzles.

3. In a can washing machine, a housing, guide means leading through the housing through which the cans are movable, a shaft

extending through the housing, a rotatable member on the shaft having radial arms for engagement with the cans, a grooved pulley keyed to the shaft, a drive pulley loosely mounted on the shaft, co-engaging fingers carried by the two pulleys, a pivoted lever having a yoke engaging the grooved pulley whereby lateral movement of the lever will actuate the grooved pulley to move the fingers thereon in the path of the fingers on the loosely mounted pulley whereby to impart rotative movement to the shaft, and a fluid control valve having connection with the lever whereby the movement of the arms and the valve may be controlled simultaneously.

In testimony that I claim the foregoing I have hereunto set my hand at Dundas, in the county of Calumet and State of Wisconsin.

JOSEPH WOLFINGER.
